UNITED STATES PATENT OFFICE.

CHARLES LE G. FORTESCUE, OF PITTSBURGH, PENNSYLVANIA, ASSIGNOR TO WESTINGHOUSE ELECTRIC & MANUFACTURING COMPANY, A CORPORATION OF PENNSYLVANIA.

LIGHTNING-ARRESTER.

1,311,503.

Specification of Letters Patent. Patented July 29, 1919.

Application filed March 14, 1917. Serial No. 154,756.

To all whom it may concern:

Be it known that I, CHARLES LE G. FORTESCUE, a subject of the King of England, and a resident of Pittsburgh, in the county of Allegheny and State of Pennsylvania, have invented a new and useful Improvement in Lightning-Arresters, of which the following is a specification.

My invention relates to devices for protecting electrical circuits and the apparatus associated therewith from abnormal high-potential stresses, such as may be occasioned by lightning discharges, static disturbances and the like.

More particularly, my invention relates to lightning arresters that are adapted to be directly inserted in transmission line conductors and are devoid of ground connections or discharge paths to ground, thereby eliminating the danger that arises when the dynamo currents tend to flow to ground in the paths initially established by the discharge of the high-frequency or high-potential impulses.

For the protection of transmission lines operating at high voltages, it is desirable to absorb the energy of disturbances by employing protective devices which are devoid of ground connections because ground connections impair the insulating properties of the transmission conductors as well as those of the electrical apparatus connected in circuit. Moreover, danger frequently arises by having ground connections because of the possibility of the arcing grounds having critical frequencies that may tend to establish resonant conditions in the circuits.

It has been proposed to employ energy-absorbing devices which shall be directly connected in circuit with the transmission line conductors and shall comprise choke coils that will permit the line currents of normal frequency to pass therethrough without substantial impedance, and resistors connected in shunt to the choke coils that shall absorb the energy of such disturbances as may be directed therethrough by reason of the inductive impedance presented by the choke coils. Lightning arresters of this general character are set forth in U. S. Patent No. 1,034,197 and U. S. Patent No. 1,217,453.

In the latter patent, the protective device comprises a choke coil and energy-absorbing means associated therewith. The electrical equivalent of this device may be repre-

sented, under certain conditions, by a choke coil in which the several convolutions are connected in shunt to resistance elements and, under other conditions, by a choke coil in which the several convolutions are connected to resistors and condensive elements. It is to this particular class of protective devices that my present invention is directed.

For a better understanding of the nature and scope of my invention, reference may be had to the following description and the accompanying drawing in which Figure 1 is a view, partially in section and partially in side elevation, of a protective device constructed in accordance with my invention; Fig. 2 is a diagram illustrating the electrical equivalent for the device of Fig. 1, and Fig. 3 is another diagram that illustrates the electrical equivalent of the device of Fig. 1, under certain conditions.

Referring to Fig. 1, a choke coil 1 made in any form and of a film-forming metal, preferably aluminum, is immersed in a body of electrolyte 2 that is contained in a tank 3. The tank 3 is mounted upon insulating supports 4 and is provided with a cover 5 through which leads 6 of the choke coil 1 project. Terminals 7 of the leads 6 provide means for connecting a line conductor 8 to the protective device. The choke coil 1 is, therefore, directly inserted in circuit with the line conductor 8 and is adequately insulated from ground, thereby precluding any current from flowing to ground.

The electrolyte 2 possesses the property of forming a high-resistance film of high specific inductive capacity upon the exterior surface of the choke coil 1 which, under ordinary conditions, suffices to confine the line currents to the choke coil. When disturbances or high-frequency impulses impinge upon the coil 1, the resultant potential stress occasioned by the inductive reactance offered by the coil is sufficient to disrupt this resistance film. A non-inductive path is consequently provided for the flow of the disturbance through the body of the electrolyte which serves as a resistor to absorb the energy of the disturbance.

To more fully understand the operation of my protective device, reference may be had to Fig. 2 in which a structure is diagrammatically illustrated that is the electrical equivalent of the device of Fig. 1. In

Fig. 2, an inductance coil 9 may represent the coil 1 of Fig. 1. Resistance elements 10 and condensive elements 11 are connected in shunt to the convolutions of the coil 9, as shown. The condensive elements 11 represent, diagrammatically, the electrostatic capacity that is imparted by the films and developed between adjacent convolutions of the coil 1 when very high-frequency impulses are impressed upon the coil. The resistors 10, shunting the condensers 11, represent the resistance of the discharge paths through the body of electrolyte between adjacent convolutions of the coil. As the frequency of the impulses impressed upon the coil 9 increases, the resultant potentials exert a greater and greater electrical pressure upon the separate convolutions of the coil. As a result, larger and larger quantities of energy are forced to flow through the resistors 10 and the condensers 11 by reason of the decreasing resistance offered by the resistance films formed upon the coil. In this manner, the energy forced to flow through the elements 10 and 11 is dissipated as heat.

The device of Fig. 2 is selective for alternating currents of any frequency; that is, a circuit comprising the proper amount of inductive reactance and condensive reactance to constitute a parallel resonant circuit for a certain frequency will be selected by impulses of that frequency. These impulses will consequently cause circulating currents of the same frequency to flow in the selected resonant circuits thus established where the energy of the impulses will be dissipated in the form of heat. Each convolution of the coil 9 possesses the same electrostatic capacity with respect to each and all the remaining convolutions. This property of the device arises from the coil being immersed in a body of electrolyte, as shown in Fig. 1 and, as a consequence, a multiplicity of resonant circuits is available in a single device.

The electrical equivalent of the device shown in Fig. 1 may, during complete breakdown of the film, be represented by the choke coil 9 of Fig. 3 in which resistance elements 10 only are connected between adjacent convolutions of the coil.

In Fig. 1, the coil 1 may be considered as being embedded in the resistance material or electrolyte 2 which, when the resistance films upon the coil are disrupted, serves as a means for dissipating, as heat, the energy absorbed from the disturbances. After the disturbance has been absorbed or its amplitude reduced to a sufficiently low value, the disrupted films upon the coil 1 are automatically reformed by reason of the properties possessed by the electrolyte 2. In this instance, the protective device is automatically restored to its original state without replac-

ing any of the elements embodied in the structure. The character of the electrolyte 2 may be modified to increase or decrease its resistance properties.

It will be understood by those skilled in the art that embodiments of my invention, other than those shown and described, may be made without departing from the spirit and scope of the appended claims.

I claim as my invention:

75

1. A protective device comprising a load-current-carrying inductance coil formed of a film-forming metal, and a body of electrolyte within which said coil is immersed.

80

2. A protective device comprising a load-current-carrying inductance coil of film-forming metal, and an electrolyte in contact with the coil for forming resistance films on the exposed surfaces thereof.

85

3. A protective device comprising a load-current-carrying inductance coil of film-forming metal, and an electrolyte in contact with the coil for forming high-resistance films on the exposed surfaces thereof and inserting resistance paths between adjacent convolutions of the coil, independent of the coil conductor.

90

4. A protective device comprising a load-current-carrying inductance coil of film-forming metal, and an electrolyte in contact with the coil for forming resistance films on the exposed surfaces thereof, said electrolyte serving as a conducting path between adjacent convolutions of the coil for currents that are impeded in their flow through said coil.

95

5. A protective device comprising a load-current-carrying inductance coil having a high-resistance film formed on the exposed surfaces thereof, and a body of electrolyte in which said coil is immersed and which serves to provide resistance shunt paths between adjacent convolutions of the coil for currents that are impeded in their flow through the coil.

100

6. A protective device comprising a load-current-carrying inductance coil of film-forming metal, and a body of electrolyte for automatically reforming said films on the coil when they are disrupted, said electrolyte serving as energy-consuming means for impulses that are directed therethrough by the reactance of said coil.

105

7. A protective device comprising a load-current-carrying inductance coil of film-forming metal, and a body of electrolyte in which the coil is immersed, said electrolyte being capable of automatically reforming disrupted films on the coil and serving as energy-consuming means for electrical disturbances that disrupt the coil films.

110

8. A protective device comprising an inductive coil having a plurality of convolutions, and means providing the operative equivalent of condensive elements and re-

115

120

125

130

sistors severally connected in parallel relation between each convolution and each of the remaining convolutions.

9. A protective device comprising an inductive coil having a plurality of convolutions, and means providing the operative equivalent of condensive elements severally connected to the convolutions of said coil and a common junction point and of resistors severally connected in shunt relation to said apparent condensive elements.

10. A protective device comprising an inductive coil having a plurality of convolutions, and means providing the operative

equivalent of condensive elements severally connected to the convolutions of said coil and jointly adapted to provide a parallel resonant circuit, in conjunction with portions of said choke coil, for each of a plurality of operating frequencies.

11. A protective device comprising a normally energized current-carrying inductance coil formed of a film-forming metal, and a body of electrolyte within which said coil is immersed.

In testimony whereof I have hereunto subscribed my name this 8th day of March 1917.

CHARLES LE G. FORTESCUE.
